UNITED STATES PATENT OFFICE.

RICHARD SCHLETTER, OF PHILADELPHIA, PENNSYLVANIA.

DESIGN FOR A STOCKING.

Application filed March 24, 1921. Serial No. 455,161. Term of patent 14 years.

To all whom it may concern:

Be it known that I, RICHARD SCHLETTER, a citizen of Germany, residing at Philadelphia, in the county of Philadelphia and State of Pennsylvania, have invented a new, original, and ornamental Design for a Stocking, of which the following is a specification, reference being had to the accompanying drawing, forming part thereof.

The figure is a front view of a stocking showing my new design.

The stocking disclosed in this application presents a strip of V-shaped contrasting material, weave or other configuration compared with the remaining portion of the stocking.

I claim:

The ornamental design for a stocking, as shown and described.

In testimony whereof I affix my signature.

RICHARD SCHLETTER.
